UNITED STATES PATENT OFFICE.

FRED VAN FLEET AND GEORGE ERIEG GRAFF, OF WILLIAMSPORT,
PENNSYLVANIA.

TYPE-WRITER.

SPECIFICATION forming part of Letters Patent No. 425,589, dated April 15, 1890.

Application filed December 9, 1889. Serial No. 383,090. (No model.)

To all whom it may concern:

Be it known that we, FRED VAN FLEET and GEORGE ERIEG GRAFF, citizens of the United States, residing at Williamsport, in the county 5 of Lycoming and State of Pennsylvania, have invented certain new and useful Improvements in Type-Writers; and we do hereby declare the following to be a full, clear, and exact description of the invention, such as 10 will enable others skilled in the art to which it appertains to make and use the same.

The liability of type to become soiled and to make a blurred impression is well-known as a serious impediment to the continuous 15 and satisfactory use of type-writing machines. Frequent cleaning becomes necessary. To facilitate this brushes and similar devices have been attached to such machines and provided with suitable hand-wheels or 20 cranks and intermediate connections, whereby such brushes are moved over the face of the types to clean them without the necessity of introducing into the machine any brush, cloth, or other article not ordinarily connected 25 thereto. As an improvement on such devices we employ an oscillating brush, which is actuated by the machine itself, and which sweeps over all the type in one motion. It is also arranged to be operated by hand, if preferred. 30

Our invention consists, therefore, in the improvements in construction and combination hereinafter particularly set forth and claimed.

35 In the accompanying drawings, Figure 1 represents a rear elevation of a Remington type-writing machine provided with an automatic brush-operating attachment embodying our invention. Fig. 2 represents a central vertical 40 section of the same from front to rear. Fig. 3 represents a detail perspective view of the brush-operating devices. Fig. 4 represents a plan of the brush-type basket and part of the brush-operating lever, the type-bars being 45 shown in cross-section.

A designates the frame of the machine; B, the carriage for the feed-rolls and paper, movable across the top of said frame from side to side on guide-bars C C'; D, the main 50 spring, drawing said carriage from right to left by strap D'; E, the rack-bar pivoted on

rear guide-bar C', but connected to said carriage and provided on its under side with rack E'; F, the escapement, having pawls f f' engaging with said rack to govern the 55 movement of the carriage from right to left and convert it into a step-by-step motion of less or greater intervals, (though uniform, of course, in either case,) according to whether said escapement is acted on by the buttons or 60 keys G, through button or key levers H, lower cross-bar I, connecting-rods J, and upper cross-bar K, or by treadle-bar or space-bar L and its rearwardly-extending arms L', bearing directly on said lower cross-bar. 65

The rack-bar is provided on the opposite side of its pivotal line from the rack E' with a bent or angular arm M, having a terminal thumb-piece m, whereby said angular arm may be depressed for lifting the rack E' out 70 of engagement with said escapement-pawls. This is usually done to allow the retraction of the carriage. The same result may also be attained by depressing the rear end of the feed-roll lever N, which overhangs this angular arm M. By lifting the forward or handle end of this lever, which is pivoted to the carriage, this depression is effected, and simultaneously the feed-rolls O P, journaled in said carriage, are driven by a pawl n on said feed- 80 roll lever, engaging a ratchet-wheel p on the shaft of one of said rolls to effect the required line-spacing. This lever is also provided with a replacing-spring n'. Each button-lever or key-lever is connected by a rod h to a type- 85 bar H', the series of type-bars and types forming the type-basket of elliptical downward opening. Across the top of said type-basket extends the inking-ribbon i, winding at its ends on rollers j. The escapement F is provided at its base with a sleeve F', turning on a shaft or rod Q, which is fixed to the rear of frame A. 90

All of the parts thus far referred to are old and well known, and I do not deem it necessary to describe further the details of the ordinary Remington machine. 95

R designates a rack attached to rack-bar E, but entirely distinct from the ordinary rack E', already described. It meshes, when said 100 rack is lifted as before described, with a gear-wheel S on a short shaft T, and has either

more or less than half the number of teeth of said wheel to avoid locking the latter on the lower "dead" central position of the pitman, hereinafter described. Said shaft T is journaled in the upwardly-extending walls of a U-shaped bearing-bracket S', which is detachably fastened to frame A by screws s, or in any other convenient manner. These screws also hold in place the stop t, which prevents the rack-bar from rising too far. This is the ordinary rack-bar stop of such machines, except that we have recessed it at t' to avoid contact with the wheel S.

When our type-cleaning devices are to be applied to a Remington machine or any other of similar construction in this respect, the screws s are withdrawn, the bearing-bracket S' is placed on the base part of said stop, and the stop and bracket together are secured to said frame by said screws. The shaft T has a crank-arm T' on it, from which a pitman U extends down to the brush-operating arm or lever V, the connection between them being at or near the outer end of the latter. The other end of said lever carries a brush W of such shape as to fit the lower opening of the type-basket, so that an upward motion of said brush will carry it over all the types at once. The middle part of said arm or lever V is attached to a yoke or U-shaped suspending bracket X, which is loosely hung at its ends on the escapement shaft or rod Q aforesaid, or its center pins or bearings. Thus the said brush-operating arm or lever V is not pivoted directly, but suspended pivotally, so as to have its fulcrum-point considerably above the lever itself, making the upward and downward motion of the brush more nearly vertical than it would be in the former case. The downward motion of pitman U causes the upward motion of said brush, and the downward motion of the latter is caused by the action of a retracting spring Y extending from bracket S to arm V. The attachment of said arm or lever V to bracket or yoke X is by means of a clamping-plate Z, which fits on said arm, the latter resting in its turn on the lower part of said yoke. This clamping-plate is fastened to the latter by screws z. These may be loosened and the said bar or lever may be slipped farther in or out before tightening them again, thus adjusting easily the length of the throw and allowing compensation for wear and such contraction or expansion as may be due to changes of temperature.

As the brush-operating rack R can engage with the gear-wheel S, arranged above it, only when the rack-bar and rack E' are lifted so high that the latter no longer engages the escapement, it follows that the operation of type cleaning, when the devices are arranged and combined as shown, cannot proceed simultaneously with that of printing nor with that of spacing; but the shifting of the carriage from side to side of the frame, either in retracting it or in shifting forward for dating or other purposes, is an equally necessary step

in the operation of the machine, and every time the feed-roll lever is moved to allow this shifting the brush is vibrated across the types as a necessary incident of such motion. The brush-operating arm or lever V may of course be operated by hand also, the pitman U being first detached by opening the eye at its lower end, which may be a spring-eye, if preferred) to allow this method of working; but the automatic action of our oscillating type-cleaning brush is the most important feature of our invention, and the latter would include a brush capable of cleaning all the type at once and its operating-connections, whatever the kind or style of type-writing machine to which they may be applied, and whether attached to the shifting mechanism, as in the instance illustrated, or otherwise, the essential distinction being that such a brush must be actuated by some part of the normal operation of the machine, in order that it may not require individual thought and effort, nor be liable to the risk of neglect. With such an attachment the act of cleaning must be very frequent, and the machine can be operated continuously, and the types will never become soiled, so as to deface the impression.

The brush may be made cheaply and easily replaced when worn out.

A machine such as the one shown will need no modification for the attachment of the brush-operating devices, except recessing the rack-bar stop very slightly, the escapement-shaft or its center pins or bearings being made to do double duty, and the rack-bar stop temporarily moved, as described. Of course, the form and material of the brush may vary as needed or desired.

Having thus described our invention, what we claim as new, and desire to secure by Letters Patent, is—

1. In a type-writing machine, the combination of a type-cleaning brush movable at one motion over all the type and away therefrom with the type-writing and paper-shifting mechanism and connections between said brush and a moving part of said machine, in order that the brush may be operated, as above stated, by the normal working of the machine, for the purpose set forth.

2. A type-writing machine provided with an automatic oscillating brush or type-cleaner, for the purpose set forth.

3. In a type-writing machine, the combination of the movable rack-bar, the feed-roll lever arranged opposite an attachment of said rack-bar for operating the latter, a type-cleaning brush, and connections between said rack-bar and said brush, substantially as set forth.

4. In a type-writing machine, a rack-bar provided with two racks and movable upward and downward, in combination with an escapement engaging one of said racks when said rack-bar is in one position, and a gear-wheel engaging the other rack when said rack-bar is in the other position, a type-cleaning

- brush, and connections between said gear-wheel and said brush for automatically operating the latter, substantially as set forth.
5. In combination with a type-cleaning brush and its lever, a yoke to which said lever is attached, the said yoke being adapted to be suspended from the escapement-shaft or escapement-shaft centers of a type-writing machine, substantially as set forth.
10. 6. In combination with the type-cleaning brush and its lever, a yoke hung pivotally to points above said lever and a clamp or set-screw, adjustably securing said lever to said yoke, substantially as set forth.
15. 7. In combination with a type-cleaning brush and its lever, a crank-shaft, pitman, and retracting-spring for vibrating the said lever, and a rack and wheel for rotating said shaft, the rack being movable with the carriage of the type-writing machine, substantially as set forth.
20. 8. In combination with a type-cleaning brush and the carriage of a type-writing machine, a rack and wheel, a pitman, a crank-shaft for said wheel, and a brush-carrying arm or lever, the rack having thereon either more or less than half the number of teeth

in said wheel to avoid dead-centering, substantially as set forth.

9. In a type-writing machine, the combination of an automatic oscillating type-cleaning brush with the types, the operating mechanism, and connections whereby the brush will be caused to clean said type by the normal operation of the machine, substantially as set forth. 30

10. A type-writing machine provided with an automatically-operated oscillating type-cleaning device or brush, said brush being also adapted to be operated by hand, substantially as set forth. 40

11. In a type-writing machine, the combination of a type-cleaning brush arranged within the type-basket with the carriage and intervening mechanism operating said brush automatically, for the purpose set forth. 45

In testimony whereof we affix our signatures in presence of two witnesses.
